PIPE TONGS

Dorse L. McGhee, 578 Fleming Road,
Cincinnati 31, Ohio

Filed Oct. 18, 1963, Ser. No. 77,045

Term of patent 14 years

(Cl. D41—1)

FIG. 2

FIG. 1

FIG. 4

FIG. 1 is a front elevational view of the pipe tongs, showing my new design, the rear view being identical;

FIG. 2 is a side elevational view thereof;

FIG. 3 is a top plan view thereof; and

FIG. 4 is a bottom plan view thereof.

I claim:

The ornamental design for pipe tongs, as shown and described.
